(57) **ABSTRACT**

A bidet with an integrated built-in water tank, including a seat, a water inlet assembly, and a jetting assembly. The seat includes a bidet main body, a shell, and a partition; the bidet main body includes a bedpan and a drain pipe; the shell is arranged at a periphery of the bidet main body; the shell includes a front sidewall, a bottom wall, a left sidewall, a right sidewall, and a rear sidewall; a bottom opening is defined between the front sidewall and the bottom wall; the partition extends upwardly from the bottom wall; the partition, the bottom wall, the left sidewall, the right sidewall, and the rear sidewall enclose to form a water tank that is opened upwardly; the partition, the shell, and the bedpan are of an integrated ceramic structure; the water inlet assembly and the jetting assembly are disposed in the water tank.

**BIDET WITH INTEGRATED BUILT-IN
WATER TANK**

CROSS REFERENCE

This application is a Continuation of the U. S. application Ser. No. 18,458,461 filed on Aug. 30, 2023, and entitled "BIDET WITH INTEGRATED BUILT-IN WATER TANK", now pending, the entire disclosures of which are incorporated herein by reference.

TECHNICAL FIELD

The present disclosure relates to technical field of sanitary ware, and in particular to a bidet with an integrated built-in water tank.

BACKGROUND

Bidets, serving as toilets, are conventionally arranged with built-in water tanks that can be divided into two kinds, one is that the water tank and the seat are separated with the water tank being placed in the wall, the other is that the water tank and the seat are installed in an integrated (one-piece) manner. The split-type tanks are not as popular as integrated-type tanks because they are not easy to install. The internal structure of the seat is complex, such as the lower surface of the bidet main body, and the curved sewage pipe, and the seat is usually a ceramic structure. Therefore, it is necessary to provide multiple process holes on the shell of the seat in order to facilitate the manufacture of the seat, for example, the process holes are provided between a bottom wall of the shell and a front sidewall of the shell. As a result, water cannot be stored between the shell and the bidet main body.

In order to facilitate manufacturing and installation, the existing bidet with an integrated built-in water tank is generally designed that a water tank is arranged at a top of a rear end of the seat, or a plastic water tank is arranged in an inner cavity of the rear end of the seat. Further, since a sufficient height difference is required, it is necessary to adopt a water inlet valve and a water pump or pressurize the air in the integrated water tank. However, these technical solutions have problems that the water storage is in a small amount and water supply through the inlet valve is too slow due to low water pressure in the water consumption peak period, which may lead to cases that the bidet cannot be flushed even in one time. In addition, for the designs where the water tank is arranged on the top, the installation space of the intelligent toilet cover will be occupied, and the manufacturing difficulty of the seat is improved; for the designs of the plastic water tanks, problems also exist of resonant noise from the plastic tank and smart toilet cover when the pump starts the water, as well as of water leakage due to deterioration after a longer period of use.

SUMMARY OF THE DISCLOSURE

The main purpose of the present disclosure is to propose a bidet with an integrated built-in water tank, aiming at solving the technical problems of the existing bidet with an integrated built-in water tank having a low water storage capacity in the water tank, unreliable flushing, and insufficient practicality.

In order to achieve the above purposes, the present disclosure provides a bidet with an integrated built-in water

tank, including a seat, a water inlet assembly, and a jetting assembly; wherein the seat includes a bidet main body, a shell, and a partition;

the bidet main body includes a bedpan and a drain pipe in communication with the bedpan;

the shell is arranged at a periphery of the bidet main body;

the shell includes a front sidewall, a bottom wall, a left sidewall, a right sidewall, and a rear sidewall; a bottom opening is defined between the front sidewall and the bottom wall facing a front portion of the bedpan;

the partition extends upwardly from the bottom wall; the partition, the bottom wall, the left sidewall, the right sidewall, and the rear sidewall enclose to form a water tank that is opened upwardly; the partition, the shell, and the bedpan are of an integrated ceramic structure;

the water inlet assembly and the jetting assembly are disposed in the water tank; the water inlet assembly includes a water inlet pipe and a water valve assembly connected in series to the water inlet pipe; the jetting assembly includes a jetting pipe and a water pump connected in series to the jetting pipe, and the jetting pipe is in communication with the bedpan.

In some embodiments, the rear sidewall defines a water inlet installation hole, and the water inlet assembly further includes a water inlet fitting; an outlet of the water inlet fitting is connected to an inlet of the water inlet pipe; the water inlet fitting is removably connected to the water inlet installation hole.

In some embodiments, the rear sidewall includes a base and a bulge that bulges inwardly from the base; the bulge defines a cavity that is opened toward an outside; the water inlet installation hole is defined on the bulge and is in communication with the cavity; an outer end of the water inlet fitting is disposed in the cavity.

In some embodiments, the bulge is connected to a lower portion of the base, and the bulge includes a top plate and an enclosure plate; the top plate extends forwardly from an inner surface of the base, the enclosure plate extends upwardly from the bottom wall, the enclosure plate is connected to the top plate and the base, and the enclosure plate, the top plate, the base, and the bottom wall enclose to define the cavity; the water inlet installation hole is defined on the top plate, and the water inlet pipe and the water valve assembly are disposed above the bulge.

In some embodiments, the bulge is connected to an upper portion of the base, the bulge includes a top plate, an enclosure plate, and an installation plate; the top plate extends forwardly from an inner surface of the base, the installation plate extends downwardly from a front edge of the top plate, and the enclosure plate is connected to the top plate and the installation plate; the enclosure plate, the top plate, and the installation plate enclose to define the cavity; the water inlet installation hole is defined on the installation plate, and the water inlet pipe and the water valve assembly are disposed on a front side of the bulge.

In some embodiments, the water inlet fitting includes a fitting body, a sealing ring, and a fastener; the fitting body includes a tube portion and a limiting flange disposed on an outer peripheral surface of an inner end of the tube portion, and the outer peripheral surface of the tube portion defines an outer thread; the tube portion passes through the water inlet installation hole; the limiting flange is disposed on an inner side of the rear sidewall, the sealing ring is disposed between the limiting flange and the rear sidewall, and the fastener is threadedly mated with the tube portion and disposed on an outer side of the rear sidewall.

In some embodiments, the partition extends upwardly to be connected to the bedpan, and an upper portion of the rear sidewall defines a window connected to an outside.

In some embodiments, the drain pipe has a curved portion extending into the water tank; the drain pipe is arranged in the middle in a left-right direction; the water inlet assembly is disposed on a first side of the drain pipe, and the water pump is disposed on a second side of the drain pipe, the first side and the second side being opposite to each other in the left-right direction.

In some embodiments, an inner wall surface of an upper portion of the bedpan defines an annular flushing groove; the jetting assembly further includes a three-way valve; the jetting pipe includes a main path, a first branch path connected to an outlet of the three-way valve, and a second branch path connected to another outlet of the three-way valve; the main path is connected to an outlet of the water pump and an inlet of the three-way valve; an outlet of the first branch path is in communication with a bottom of the bedpan, and an outlet of the second branch path is in communication with the annular flushing groove on the upper portion of the bedpan.

In some embodiments, the partition extends upwardly to be connected to the bedpan, and the partition defines a through hole for the second branch path to pass through.

As proposed by the present disclosure, the bidet with an integrated built-in water tank is arranged with an integrated ceramic structure of the partition, the shell, and the bedpan. In this way, while retaining the bottom opening, the upwardly-opened water tank is formed by enclosing the partition, the bottom wall, the left sidewall, the right sidewall, and the rear sidewall, such that the space in a rear portion of the seat is fully utilized, and the formed water tank has a large capacity and can cooperate with the water pump for a long and stable flushing operation. Moreover, since the bottom opening is retained and the water tank has an opening facing upward, an outer surface of the bidet main body can be easily accessed from the outside, such that the setting of the water tank does not affect the shaping of the bidet main body. The opening on an upper portion of the water tank also facilitates the installation of a smart toilet cover, whereby a lower raised portion at a rear end of the smart toilet cover can be embedded in the water tank, thereby making the overall height of the product lower, which in turn enhances the installation adaptability or reduces the space occupation. Since the water tank is constructed of ceramic material and is integrally structured with the bidet main body and the rest of the shell, it is less likely to resonate with vibration of the water pump, which can provide the user with a better silent experience.

A bidet with an integrated built-in water tank, including a seat, a water inlet assembly, and a jetting assembly; wherein the seat includes a bidet main body, a shell, and a partition; the bidet main body includes a bedpan and a drain pipe in communication with the bedpan;

the shell is arranged at a periphery of the bidet main body; the shell includes a bottom wall, a left sidewall, a right sidewall, and a rear sidewall; the rear sidewall includes a first rear sidewall and a second rear sidewall disposed facing each other in a front-rear direction, the second rear sidewall defines a hanging hole and a drain through hole;

the partition and the first rear sidewall are disposed opposite to each other in the front-rear direction and both extend upwardly from the bottom wall, and a front portion of the bedpan protrudes from a front side of the partition; the partition and the first rear sidewall are

disposed on a front side of the second rear sidewall; an installation cavity is defined between the first rear sidewall and the second rear sidewall, and the drain pipe passes through the first rear sidewall and has an external connection end extending into the installation cavity, the external connection end being disposed at a position corresponding to the drain through hole; the partition, the first rear sidewall, the bottom wall, the left sidewall, and the right sidewall enclose to form a water tank that is opened upwardly;

the water inlet assembly includes a water inlet pipe and a water valve assembly connected in series to the water inlet pipe; the jetting assembly includes a jetting pipe and a water pump connected in series to the jetting pipe; an inlet of the water pump and an inlet of the water inlet pipe are arranged in the water tank, and the jetting pipe is in communication with the bedpan.

In some embodiments, the bidet further includes an overflow pipe passing through the first rear sidewall; wherein an inlet end of the overflow pipe is disposed in the water tank, and an outlet end of the overflow pipe extends into the installation cavity.

In some embodiments, the outlet end of the overflow pipe is in communication with the external connection end.

In some embodiments, the seat further includes a connector protruding on a rear surface of the first rear sidewall and connected to an outer peripheral surface of the external connection end; an inner cavity of the connector is in communication with an inner cavity of the external connection end; an overflow installation hole is defined on the first rear sidewall corresponding to the connector and in communication with the inner cavity of the connector, and the outlet end of the overflow pipe is sealingly fixed to the overflow installation hole.

In some embodiments, an outer peripheral surface of the outlet end of the overflow pipe is arranged with a limiting flange and an elastic snap; the limiting flange and the elastic snap are spaced apart in a drainage direction of the overflow pipe;

the bidet further includes a sealing ring sleeved on the outer peripheral surface of the outlet end of the overflow pipe, and the elastic snap abuts against a rear surface of the first rear sidewall;

the sealing ring is pressed between the limiting flange and a front surface of the first rear sidewall and is sealingly mated with the limiting flange and the first rear sidewall, respectively.

In some embodiments, the first rear sidewall defines a water inlet installation hole, and the water inlet assembly further includes a water inlet fitting; an outlet of the water inlet fitting is connected to an inlet of the water inlet pipe; the water inlet fitting is removably connected to the water inlet installation hole; the partition, the first rear sidewall, the shell, the bedpan, and the connector are of an integrated ceramic structure.

In some embodiments, the overflow pipe has a reservoir section being in the form of an arch with a concave side facing upward.

In some embodiments, the overflow pipe includes an odor barrier structure; the overflow pipe further includes an inline section and a reservoir section connected to an upper end of the inline section; the inlet end of the overflow pipe is formed at the reservoir section; the odor barrier structure is formed at the reservoir section, and the outlet end of the overflow pipe is formed at a lower end of the inline section; the inline section extends in a vertical direction, and a main portion of the reservoir section is in a form of an arch with

a concave side facing upward; the reservoir section has a connection port arranged downwardly to be connected to the upper end of the inline section; the water inlet assembly further includes a water replenishment assembly; the water replenishment assembly includes a water replenishment valve, and a water replenishment pipe; a water replenishment inlet of the water replenishment pipe is connected to the water replenishment valve, and a water replenishment outlet of the water replenishment pipe is connected to the inlet end of the overflow pipe.

In some embodiments, the bidet further includes a side branch pipe; wherein an end of the side branch pipe is in communication with an upper portion of the bedpan, and the other end of the side branch pipe is in communication with the inlet end of the overflow pipe.

In some embodiments, the overflow pipe includes an odor barrier structure; the overflow pipe further includes an inline section and a reservoir section connected to an upper end of the inline section; the inlet end of the overflow pipe is formed at the reservoir section; the odor barrier structure is formed at the reservoir section, the inline section extends along a front-rear direction, and the outlet end of the overflow pipe is formed at a rear end of the inline section; a main portion of the reservoir section is in a form of an arch with a concave side facing upward;

the bidet further includes an extraction assembly, the extraction assembly including an extraction pipe and an extraction fan connected in series with the extraction pipe; an end of the extraction pipe is in communication with the upper portion of the bedpan, and the other end of the extraction pipe is in communication with a downstream portion of a reservoir area of the reservoir section.

In some embodiments, the inlet end of the overflow pipe is arranged with an inlet grill defining an insertion hole, and the water replenishment outlet of the water replenishment pipe 35c is inserted with the insertion hole.

In some embodiments, the shell further includes a front sidewall disposed on the front side of the partition; a first opening is defined between the front sidewall and the partition and disposed at a bottom and corresponding to the front portion of the bedpan; a second opening is defined between the front sidewall and the first rear sidewall and disposed at the bottom; the partition, the first rear sidewall, the shell, and the bedpan are of an integrated ceramic structure.

As proposed by the present disclosure, the bidet with an integrated built-in water tank is arranged with the partition and the first rear sidewall which can directly cooperate with the shell to enclose to form the water tank, thereby making full use of the irregular space at the rear portion of the seat. Further, the water tank is with a large capacity, and the setting of the water tank does not affect the shape of the bidet main body. The opening on an upper portion of the water tank also facilitates the installation of a smart toilet cover, whereby a lower raised portion at a rear end of the smart toilet cover can be embedded in the water tank, thereby making the overall height of the product lower, which in turn enhances the installation adaptability or reduces the space occupation.

A bidet with an integrated built-in water tank, including a seat, a water inlet assembly, a jetting assembly, and an overflow pipe;

wherein the seat includes a bidet main body, a shell, and a water tank; the bidet main body includes a bedpan and a drain pipe in communication with the bedpan; the shell is arranged at a periphery of the bidet main body;

the water inlet assembly and the jetting assembly are disposed in the water tank; the water inlet assembly includes a water inlet pipe and a water valve assembly connected in series to the water inlet pipe; the jetting assembly includes a jetting pipe and a water pump connected in series to the jetting pipe, and the jetting pipe is in communication with the bedpan; an inlet end of the overflow pipe extends into the water tank.

10 In some embodiments, an outlet end of the overflow pipe is in communication with the drain pipe.

In some embodiments, the shell includes a bottom wall, and a lower portion of the drain pipe is integrally connected to the bottom wall; a position, of an upper surface of the bottom wall, adjacent to the drain pipe is arranged with an installation tab being hollow; an inner cavity of the installation tab is in communication with the drain pipe, a top of the installation tab defines an overflow installation hole in communication with the inner cavity of the installation tab, and a lower end of the overflow pipe is sealingly fixed to the overflow installation hole.

In some embodiments, the shell includes a front sidewall, a bottom wall, a left sidewall, a right sidewall, and a rear sidewall; a bottom opening is defined between the front sidewall and the bottom wall facing a front portion of the bedpan;

the seat further includes a partition; the partition extends upwardly from the bottom wall; the partition, the bottom wall, the left sidewall, the right sidewall, and the rear sidewall enclose to form a water tank that is opened upwardly; the installation tab, the partition, the shell, and the bedpan are of an integrated ceramic structure.

In some embodiments, an outer peripheral surface of the outlet end of the overflow pipe is arranged with a limiting flange and an elastic snap; the limiting flange and the elastic snap are spaced apart in a drainage direction of the overflow pipe, and the elastic snap is positioned lower than a position of the limiting flange;

the bidet further includes a sealing ring sleeved on the outer peripheral surface of the outlet end of the overflow pipe, and the elastic snap abuts against an inner surface of the installation tab;

the sealing ring is pressed between the limiting flange and the installation tab and is sealingly mated with an upper surface of the limiting flange and an upper surface of the installation tab, respectively.

In some embodiments, the overflow pipe includes an odor barrier structure.

In some embodiments, the overflow pipe further includes an inline section and a reservoir section connected to an upper end of the inline section; the inlet end of the overflow pipe is formed at the reservoir section; the odor barrier structure is formed at the reservoir section, and the outlet end of the overflow pipe is formed at a lower end of the inline section.

In some embodiments, the inline section extends in a vertical direction, and a main portion of the reservoir section is in a form of an arch with a concave side facing upward; the reservoir section has a connection port arranged downwardly to be connected to the upper end of the inline section.

In some embodiments, the inline section is disposed adjacent to the drain pipe, and the reservoir section is arranged on a side of the inline section away from the drain pipe.

In some embodiments, the rear sidewall of the shell is defines a water inlet installation hole, and the water inlet

assembly further includes a water inlet fitting; an outlet of the water inlet fitting is in communication with an inlet of the water inlet pipe; the water inlet fitting is removably connected to the water inlet installation hole; the water inlet assembly further includes a water replenishment assembly; the water replenishment assembly includes a water replenishment valve, a water replenishment pipe, and a water replenishment outlet, the water replenishment valve being disposed adjacent to the water inlet fitting; a water replenishment inlet of the water replenishment pipe is connected to the water replenishment valve, and a water replenishment outlet of the water replenishment pipe is connected to the inlet end of the overflow pipe.

In some embodiments, the bidet further includes an overflow pipe and a side branch pipe; wherein an inlet end of the overflow pipe extends into the water tank, and an outlet end of the overflow pipe is in communication with the drain pipe; an end of the side branch pipe is in communication with an upper portion of the bedpan, and the other end of the side branch pipe is in communication with the inlet end of the overflow pipe; the upper portion of the bedpan defines a diversion groove arranged horizontally; both the jetting pipe and the side branch pipe are in communication with the diversion groove.

In some embodiments, the bidet further includes an overflow pipe and an extraction assembly; an inlet end of the overflow pipe extends into the water tank, and an outlet end of the overflow pipe is in communication with the drain pipe;

the overflow pipe includes an odor barrier structure, and the overflow pipe includes an inline section and a reservoir section connected to an upper end of the inline section; the inlet end of the overflow pipe is formed at the reservoir section, the odor barrier structure is formed at the reservoir section, and the outlet end of the overflow pipe is formed at a lower end of the inline section; the inline section extends in a vertical direction, and a main portion of the reservoir section is in a form of an arch with a concave side facing upward; the reservoir section has a connection port arranged downwardly to be connected to the upper end of the inline section;

the extraction assembly includes an extraction pipe and an extraction fan connected in series to the extraction pipe; an end of the extraction pipe is in communication with an upper portion of the bedpan, and the other end of the extraction pipe is in communication with the inline section.

As proposed by the present disclosure, for the bidet with an integrated built-in water tank, the inlet end of the overflow pipe extends into the water tank arranged with the water inlet assembly and the jetting assembly, such that even if the water inlet assembly malfunctions and results in an overfilling of the water, the excess water can be discharged out of the inlet end of the overflow pipe, which thereby reduces the risk of a leakage of the water from the bidet. Furthermore, due to the structure of the overflow pipe within the water tank, the bidet with an integrated built-in water tank is provided with a water level line defined by a mandatory standard.

BRIEF DESCRIPTION OF THE DRAWINGS

In order to more clearly illustrate the technical solutions in the embodiments of the present disclosure, the accompanying drawings to be used in the description of the embodiments will be briefly introduced in the following. Obviously,

the accompanying drawings in the following description are only some of the embodiments of the present disclosure, and for those skilled in the art, other accompanying drawings can be obtained based on these drawings without creative labor.

FIG. 1 is a perspective structural schematic view of a bidet with an integrated built-in water tank according to a first embodiment of the present disclosure.

FIG. 2 is a perspective structural schematic view of another angle of the bidet with an integrated built-in water tank as shown in FIG. 1.

FIG. 3 is a perspective structural schematic view of a bottom of the bidet with an integrated built-in water tank as shown in FIG. 1.

FIG. 4 is a perspective structural schematic view of another angle of the bottom of the bidet with an integrated built-in water tank as shown in FIG. 1.

FIG. 5 is a top structural schematic view of a seat in FIG. 1.

FIG. 6 is a cross-sectional structural schematic view along line A-A in FIG. 5.

FIG. 7 is an exploded structural schematic view of a water inlet assembly in FIG. 2.

FIG. 8 is a perspective structural schematic view of a bidet with an integrated built-in water tank according to a second embodiment of the present disclosure.

FIG. 9 is a perspective structural schematic view of another angle of the bidet with an integrated built-in water tank as shown in FIG. 8.

FIG. 10 is a perspective structural schematic view of a bottom of the bidet with an integrated built-in water tank as shown in FIG. 8.

FIG. 11 is a perspective structural schematic view of another angle of the bottom of the bidet with an integrated built-in water tank as shown in FIG. 8.

FIG. 12 is a cross-sectional structural schematic view of the bidet with an integrated built-in water tank as shown in FIG. 8.

FIG. 13 is a schematic view of a partially enlarged structure at B in FIG. 12.

FIG. 14 is a cross-sectional structural schematic view of a seat in FIG. 12.

FIG. 15 is an exploded structural schematic view of a water inlet assembly in FIG. 9.

FIG. 16 is a perspective structural schematic view of a bidet with an integrated built-in water tank according to a third embodiment of the present disclosure.

FIG. 17 is a schematic view of a partially enlarged structure at C in FIG. 16.

FIG. 18 is a top structural schematic view of the bidet with an integrated built-in water tank as shown in FIG. 16.

FIG. 19 is a bottom structural schematic view of the bidet with an integrated built-in water tank as shown in FIG. 16.

FIG. 20 is an exploded structural schematic structural view of the bidet with an integrated built-in water tank as shown in FIG. 16.

FIG. 21 is a perspective structural schematic view of a seat in FIG. 20.

FIG. 22 is a perspective structural schematic view of an overflow pipe in FIG. 20.

FIG. 23 is a perspective structural schematic view of another angle of the overflow pipe in FIG. 20.

FIG. 24 is a front schematic view of the overflow pipe in FIG. 20.

FIG. 25 is a perspective structural schematic view of a water inlet assembly in FIG. 20.

FIG. 26 is a perspective structural schematic view of a bidet with an integrated built-in water tank according to a fourth embodiment of the present disclosure.

FIG. 27 is another perspective structural schematic view of the bidet with an integrated built-in water tank as shown in FIG. 26.

FIG. 28 is an exploded structural schematic view of the bidet with an integrated built-in water tank as shown in FIG. 26.

FIG. 29 is a top structural schematic view of the bidet with an integrated built-in water tank as shown in FIG. 26.

FIG. 30 is a cross-sectional structural schematic view along line D-D in FIG. 29.

FIG. 31 is a cross-sectional structural schematic view along line E-E in FIG. 29.

FIG. 32 is a schematic view of a partially enlarged structure at F in FIG. 31.

FIG. 33 is a perspective structural schematic view of an overflow pipe in FIG. 26.

FIG. 34 is a perspective structural schematic view of a bidet with an integrated built-in water tank according to a fifth embodiment of the present disclosure.

FIG. 35 is a perspective structural schematic view of a bottom of the bidet with an integrated built-in water tank as shown in FIG. 34.

FIG. 36 is a top structural schematic view of the bidet with an integrated built-in water tank as shown in FIG. 34.

FIG. 37 is a cross-sectional structural schematic view along line G-G in FIG. 36.

FIG. 38 is a perspective structural schematic view of a bidet with an integrated built-in water tank according to a sixth embodiment of the present disclosure.

FIG. 39 is a perspective structural schematic view of a bottom of the bidet with an integrated built-in water tank as shown in FIG. 38.

FIG. 40 is a top structural schematic view of the bidet with an integrated built-in water tank as shown in FIG. 38.

FIG. 41 is a cross-sectional structural schematic view along line H-H in FIG. 40.

DETAILED DESCRIPTION

The technical solutions in the embodiments of the present disclosure will be described clearly and completely in the following in conjunction with the accompanying drawings in the embodiments of the present disclosure, and it is obvious that the described embodiments are only a part of the embodiments of the present disclosure and not all of the embodiments. Based on the embodiments in the present disclosure, all other embodiments obtained those skilled in the art without creative labor fall within the scope of the present disclosure.

Referring to FIGS. 1-7 or FIGS. 8-15, in the first and second embodiments, the present disclosure proposes a bidet 100, 200 with an integrated built-in water tank, including a seat 10a, 10b, a water inlet assembly 40a, 40b, and a jetting assembly 50; the seat 10a, 10b includes a bidet main body 11, a shell 14a, 14b, and a partition 30.

The bidet main body 11 includes a bedpan 12 and a drain pipe 13 connected to the bedpan 12.

The shell 14a, 14b is arranged at a periphery of the bidet main body 11; the shell 14a, 14b includes a front sidewall 15, a bottom wall 16, a left sidewall 17, a right sidewall 18, and a rear sidewall 19, 24; a bottom opening 29 is defined between the front sidewall 15 and the bottom wall 16 facing a front portion of the bedpan 12.

The partition 30 extends upwardly from the bottom wall 16; the partition 30, the bottom wall 16, the left sidewall 17, the right sidewall 18, and the rear sidewall 19, 24 enclose to form a water tank 31 that is opened upwardly; the partition 30, the shell 14a, 14b, and the bedpan 12 are of an integrated ceramic structure.

The water inlet assembly 40a, 40b and the jetting assembly 50 are disposed in the water tank 31; the water inlet assembly 40a, 40b includes a water inlet pipe 41 and a water valve assembly 42 connected in series to the water inlet pipe 41; the jetting assembly 50 includes a jetting pipe 51 and a water pump 52 connected in series to the jetting pipe 51, and the jetting pipe 51 is connected to the bedpan 12.

In the embodiments, the seat 10a, 10b is a main structure; the water inlet assembly 40a, 40b and the jetting assembly 50 are disposed on the seat 10a, 10b; the bidet main body 11 and the shell 14a, 14b of the seat 10a, 10b may be adopted from the related art; the bedpan 12 is configured to receive excrement, and the jetting assembly 50 is configured to jet water into an inner cavity of the bidet main body 11, so as to discharge the excrement into a pipe connected to a septic tank through the drain pipe 13. The drain pipe 13 is usually arranged with a water reservoir for odor prevention, and the drain pipe 13 may be further arranged with an upwardly-arched curved portion to prevent backflow. The shell 14a, 14b is not only a cosmetic part, but also provides support for the bidet main body 11. The seat 10a, 10b may be installed either on a bottom surface or on a vertical surface, such as on a wall or on a stand having a vertical installation surface. The water inlet assembly 40a, 40b and the jetting assembly 50 may be adopted from the related art; the water valve assembly 42 may be either a manual valve or an electromechanical automatic valve, such as a solenoid valve, or a purely mechanical automatic valve.

As proposed by the present disclosure, the bidet 100, 200 with an integrated built-in water tank is arranged with an integrated ceramic structure of the partition 30, the shell 14a, 14b, and the bedpan 12. In this way, while retaining the bottom opening 29, the upwardly-opened water tank 31 is formed by enclosing the partition 30, the bottom wall 16, the left sidewall 17, the right sidewall 18, and the rear sidewall 19, 24, such that the space in a rear portion of the seat 10a, 10b is fully utilized, and the formed water tank 31 has a large capacity and can cooperate with the water pump 52 for a long and stable flushing operation. Moreover, since the bottom opening 29 is retained and the water tank 31 has an opening facing upward, an outer surface of the bidet main body 11 can be easily accessed from the outside, such that the setting of the water tank 31 does not affect the shaping of the bidet main body 11. The opening on an upper portion of the water tank 31 also facilitates the installation of a smart toilet cover, whereby a lower raised portion at a rear end of the smart toilet cover can be embedded in the water tank 31, thereby making the overall height of the product lower, which in turn enhances the installation adaptability or reduces the space occupation. Since the water tank 31 is constructed of ceramic material and is integrally structured with the bidet main body 11 and the rest of the shell 14a, 14b, it is less likely to resonate with vibration of the water pump 52, which can provide the user with a better silent experience.

Further, the rear sidewall 19, 24 defines a water inlet installation hole 20, 25, and the water inlet assembly 40a, 40b further includes a water inlet fitting 43; an outlet of the water inlet fitting 43 is connected to an inlet of the water inlet pipe 41; the water inlet fitting 43 is removably connected to the water inlet installation hole 20, 25.

11

In the embodiments, the water inlet fitting 43 can facilitate connection of the water inlet pipe 41 to the municipal water pipe and support the water inlet pipe 41. In some embodiments, an outlet of the water inlet pipe 41 is arranged close to the bottom wall 16, such that less noise is generated when replenishing the water.

Further, the rear sidewall 19, 24 includes a base 21, 26 and a bulge 22, 27 that bulges inwardly from the base 21, 26; the bulge 22, 27 defines a cavity 23, 28 that is opened toward an outside; the water inlet installation hole 20, 25 is defined on the bulge 22, 27 and is in communication with the cavity 23, 28; an outer end of the water inlet fitting 43 is disposed in the cavity 23, 28.

In the embodiments, installation of the seat 10a, 10b is facilitated by hiding the water inlet fitting 43 in the cavity 23, 28 of the bulge 22, 27 such that the base 21, 26 can be closer to or fit against the vertical installation surface.

Further, referring to FIGS. 1 to 7, in the first embodiment, in order to facilitate the connection of the water pipe at the bottom and to reduce the height of a main part of the water inlet assembly 40a for facilitating the installation of the toilet cover, the bulge 22 is connected to a lower portion of the base 21, and the bulge 22 includes a top plate 221 and an enclosure plate 222; the top plate 221 extends forwardly from an inner surface of the base 21, the enclosure plate 222 extends upwardly from the bottom wall 16, the enclosure plate 222 is connected to the top plate 221 and the base 21, and the enclosure plate 222, the top plate 221, the base 21, and the bottom wall 16 enclose to define the cavity 23; the water inlet installation hole 20 is defined on the top plate 221, and the water inlet pipe 41 and the water valve assembly 42 are disposed above the bulge 22. In the embodiments, the bulge 22 is connected to the lower portion of the base 21, defining the cavity 23 with the bottom wall 16, which can simplify the setup of the bulge 22 and is conducive to minimizing the height of the top plate 221, thereby enhancing the compactness of the bidet.

Further, referring to FIGS. 8 to 15, in the second embodiment, in order to facilitate the connection of the water pipe near the top of the seat 10b and to reduce the height of a main part of the water inlet assembly 40b for facilitating the installation of the toilet cover, the bulge 27 is connected to an upper portion of the base 26, the bulge 27 includes a top plate 271, an enclosure plate 272, and an installation plate 273; the top plate 271 extends forwardly from an inner surface of the base 26, the installation plate 273 extends downwardly from a front edge of the top plate 271, and the enclosure plate 272 is connected to the top plate 271 and the installation plate 273; the enclosure plate 272, the top plate 271, and the installation plate 273 enclose to define the cavity 28; the water inlet installation hole 25 is defined on the installation plate 273, and the water inlet pipe 41 and the water valve assembly 42 are disposed on a front side of the bulge 27.

Further, referring to FIGS. 6 and 7, or referring to FIGS. 12 to 15, in the first and second embodiments, the water inlet fitting 43 includes a fitting body 44, a sealing ring 45, and a fastener 46; the fitting body 44 includes a tube portion 441 and a limiting flange 442 disposed on an outer peripheral surface of an inner end of the tube portion 441, and the outer peripheral surface of the tube portion 441 defines an outer thread; the tube portion 441 passes through the water inlet installation hole 20, 25; the limiting flange 442 is disposed on an inner side of the rear sidewall 19, 24, the sealing ring 45 is disposed between the limiting flange 442 and the rear

12

sidewall 19, 24, and the fastener 46 is threadedly mated with the tube portion 441 and disposed on an outer side of the rear sidewall 19, 24.

In the embodiments, the sealing ring 45 can be tightly pressed between the limiting flange 442 and the rear sidewall 19, 24 by screwing the fastener 46. In some embodiments, the sealing ring 45 has a tapered sealing surface, a small diameter of the sealing surface is set close to the rear sidewall 19, 24, and the small diameter of the sealing surface is less than an inner diameter of the inlet installation hole 20, 25.

Further, referring to FIGS. 1 to 6, or referring to FIGS. 8 to 12, in the first and second embodiments, the partition 30 extends upwardly to be connected to the bedpan 12, and an upper portion of the rear sidewall 19, 24 defines a window 211, 261 connected to the outside.

In the embodiments, the partition 30 extends upwardly to be connected to the bedpan 12, thereby increasing the capacity of the water tank 31, while the window 211, 261 defined on the rear sidewall 19, 24 can realize overflow and provide the possibility of touching the bidet main body 11 from another angle. It will be appreciated that in an event that the water valve assembly 42 malfunctions and the water tank 31 is overfilled, the overflow through the window 211, 261 prevents water from soaking electromechanical parts of the smart toilet cover located above.

Further, the drain pipe 13 has a curved portion extending into the water tank 31; the drain pipe 13 is arranged in the middle in a left-right direction; the water inlet assembly 40a, 40b and the water pump 52 are located on both sides of the drain pipe 13, respectively, in the left-right direction.

In the embodiments, the curved portion of the sewage pipe 13 extends into the water tank 31, meaning that the position of the partition 30 is sufficiently forward, such that it is conducive to expanding the capacity of the water tank 31. The water inlet assembly 40a, 40b and the water pump 52 are located on the both sides, which is conducive to ensuring that there is enough installation space for each other, thereby enhancing the installation efficiency.

Further, an inner wall surface of an upper portion of the bedpan 12 defines an annular flushing groove 121; the jetting assembly 50 further includes a three-way valve 53; the jetting pipe 51 includes a main path 511, and a first branch path 512 and a second branch path 513 respectively connected to two outlets of the three-way valve 53; the main path 511 is connected to an outlet of the water pump 52 and an inlet of the three-way valve 53; an outlet of the first branch path 512 is connected to a bottom of the bedpan 12, and an outlet of the second branch path 513 is connected to the flushing groove 121 on the upper portion of the bedpan 12.

In the embodiments, the jetting assembly 50 performs rinsing by two branch paths, such that a better rinsing effect can be achieved under the premise of the same amount of water; in other words, while achieving the same rinsing effect, the two branch paths may achieve a better water-saving performance.

Further, the partition 30 extends upwardly to be connected to the bedpan 12, and the partition 30 defines a through hole for the second branch path 513 to pass through.

In the embodiments, by defining the through hole on the partition 30, the second branch path 513 can be better connected to a portion of the drain pipe 13 at the foremost end, thereby enhancing the water flow in the direction from the front to the rear, and thus enhancing the rinsing effect.

In a third embodiment, referring to FIGS. 16 to 21 and FIG. 25, a bidet 300 with an integrated built-in water tank

13

proposed in the present disclosure includes a seat 10c, a water inlet assembly 30c, and a jetting assembly 40c; the seat 10c includes a bidet main body 11c, a shell 14c, and a partition 20c.

The bidet main body 11c includes a bedpan 12c and a drain pipe 13c connected to the bedpan 12c.

The shell 14c is disposed at a periphery of the bidet main body 11c; the shell 14c includes a bottom wall 15c, a left sidewall 16c, a right sidewall 17c, and a rear sidewall 29c; the rear sidewall 29c includes a first rear sidewall 21c and a second rear sidewall 18c disposed facing each other in a front-rear direction, and the second rear sidewall 18c defines a hanging hole 181c and a drain through hole 182c.

The partition 20c and the first rear sidewall 21c are disposed opposite to each other in the front-rear direction and both extend upwardly from the bottom wall 15c, and a front portion of the bedpan 12c protrudes from a front side of the partition 20c; the partition 20c and the first rear sidewall 21c are disposed on a front side of the second rear sidewall 18c; an installation cavity 24c is defined between the first rear sidewall 21c and the second rear sidewall 18c, and the drain pipe 13c passes through the first rear sidewall 21c and has an external connection end 131c extending into the installation cavity 24c, the external connection end 131c being disposed at a position corresponding to the drain through hole 182c; the partition 20c, the first rear sidewall 21c, the bottom wall 15c, the left sidewall 16c, and the right sidewall 17c enclose to form a water tank 25c that is opened upwardly.

The water inlet assembly 30c includes a water inlet pipe 31c and a water valve assembly 32cc connected in series to the water inlet pipe 31c; the jetting assembly 40c includes a jetting pipe 41c and a water pump 42c connected in series to the jetting pipe 41c; an inlet of the water pump 42c and an outlet of the water inlet pipe 31c are disposed in the water tank 25c, and the jetting pipe 41c is in communication with the bedpan 12c.

In the embodiments, the seat 10c may be a single component or may be assembled from multiple components; the seat 10c may be an integrated ceramic structure since the water tank 25c has an opening facing upward and the installation cavity 24c is defined between the first rear sidewall 21c and the second rear sidewall 18c. The bedpan 12c is configured to receive excrement, and the jetting assembly 40c is configured to jet water into an inner cavity of the bidet main body 11c, such that the excrement is discharged through the drain pipe 13c. In order to achieve a water saving effect, the jet pipe 41c may be connected to two branches, one branch jetting water from an upper edge of the bedpan 12c and the other branch jetting water from an inlet of the drain pipe 13c. The shell 14c is not only a cosmetic part, but also provides support for the bedpan 12c. The seat 10c can be suspended and mounted by using a fastener through the hanging hole 181c and a vertical surface installation structure, such as a wall or a bracket. Both the water inlet assembly 30c and the jetting assembly 40c may be adopted from the related art; the water valve assembly 32c may be either a manual or electromechanical automatic valve, such as a solenoid valve, or a purely mechanical automatic valve.

As proposed by the present disclosure, the bidet 300 with an integrated built-in water tank is arranged with the partition 20c and the first rear sidewall 21c which can directly cooperate with the shell 14c to enclose to form the water tank 25c, thereby making full use of the irregular space at the rear portion of the seat 10c. Further, the water tank 25c is with a large capacity, and the setting of the water tank 25c

14

does not affect the shape of the bidet main body 11c. The opening on an upper portion of the water tank 25c also facilitates the installation of a smart toilet cover, whereby a lower raised portion at a rear end of the smart toilet cover can be embedded in the water tank 25c, thereby making the overall height of the product lower, which in turn enhances the installation adaptability or reduces the space occupation.

Further, referring to FIGS. 16 to 18, 20, and 21 to 24, in some embodiments, the bidet 300 with an integrated built-in water tank further includes an overflow pipe 50c passing through the first rear sidewall 21c; an inlet end 51c of the overflow pipe 50c is disposed in the water tank 25c, and an outlet end 52c of the overflow pipe 50c extends into the installation cavity 24c. In this way, even if the water inlet assembly 30c malfunctions which results in overfilling, the excess water can be discharged from the inlet end 51c of the overflow pipe 50c, thereby reducing the risk of water leakage from the bidet. In addition, due to the structure of the overflow pipe 50c within the water tank 25c, the bidet is provided with a water level line defined by a mandatory standard.

Further, the outlet end 52c of the overflow pipe 50c is in communication with the external connection end 131c. In this way, the overflow pipe 50c and the drain pipe 13c can share a common connection to the external pipe.

Further, in order to facilitate lateral connection of the overflow pipe 50c to the external connection end 131c of the drain pipe 13c, the seat 10c further includes a connector 26c protruding on a rear surface of the first rear sidewall 21c and connected to an outer peripheral surface of the external connection end 131c; an inner cavity of the connector 26c is in communication with an inner cavity of the external connection end 131c. Referring together to FIG. 21, an overflow installation hole 22c is defined on the first rear sidewall 21c corresponding to the connector 26c and in communication with the inner cavity of the connector 26c, and the outlet end 52c of the overflow pipe 50c is sealingly fixed to the overflow installation hole 22c.

Further, in order to facilitate removable installation of the overflow pipe 50c with the first rear sidewall 21c and to ensure sealing between the overflow pipe 50c and the overflow installation hole 22c, an outer peripheral surface of the outlet end 52c of the overflow pipe 50c is arranged with a limiting flange 53c and an elastic snap 54c; the limiting flange 53c and the elastic snap 54c are spaced apart in a drainage direction of the overflow pipe 50c. The bidet 300 with an integrated built-in water tank further includes a sealing ring (not shown) sleeved on the outer peripheral surface of the outlet end 52c of the overflow pipe 50c, and the elastic snap 54c abuts against the rear surface of the first rear sidewall 21c; the sealing ring is pressed and clamped between the limiting flange 53c and a front surface of the first rear sidewall 21c, and is sealingly mated with the limiting flange 53c and the first rear sidewall 21c, respectively.

Further, the first rear sidewall 21c defines a water inlet installation hole 23c, and the water inlet assembly 30c further includes a water inlet fitting 36c; an outlet of the water inlet fitting 36c is in communication with an inlet of the water inlet pipe 31c; the water inlet fitting 36c is removably connected to the water inlet installation hole 23c; the partition 20c, the first rear sidewall 21c, the shell 14c, the bedpan 12c, and the connector 26c are of an integrated ceramic structure.

In the embodiments, the provision of the water inlet fitting 36c can facilitate connection of the water inlet pipe 31c to the municipal water pipe and support the water inlet pipe

31c. Since the water tank 25c is constructed of ceramic material and is integrally structured with the bidet main body 11c and the rest of the shell 14c, it is less likely to resonate with vibration of the water pump 42c, which can provide the user with a better silent experience.

Further, in order that the overflow pipe 50c also serves as an odor barrier, the overflow pipe 50c has a reservoir section 55c in the shape of an arch with a concave side facing upward.

Further, referring again to FIGS. 16 to 18, FIG. 20, and FIG. 25, in some embodiments, the water inlet assembly 30c further includes a water replenishment assembly 33c; the water replenishment assembly 33c includes a water replenishment valve 34c and a water replenishment pipe 35c; a water replenishment inlet of the water replenishment pipe 35c is connected to the water replenishment valve 34c, and a water replenishment outlet of the water replenishment pipe 35c is connected to the inlet end of the overflow pipe 50c.

In the embodiments, since the water level of the water tank 25c is too high and a scenario where overflow drainage is required through the overflow pipe 50c is in a low frequency, if the reservoir section 55c of the overflow pipe 50c is left standing for a long period of time after water is first added, an odor is generated from the water stored in the reservoir section 55c. When the reservoir section 55c is replenished by the water replenishment assembly 33c in a timely manner, the water stored in the reservoir section 55c can be replaced before the odor is generated. In addition, if the water in the reservoir section 55c is left standing for a long period of time, the water may evaporate, resulting in the odor in the drain pipe 13c entering the water tank 25c through the overflow pipe 50c and further overflowing into the ambient air outside the bidet 300 with an integrated built-in water tank. Therefore, by replenishing the water in the reservoir section 55c by the replenishment assembly 33c at appropriate time, it is possible for the overflow pipe 50c to always be in a water-tight condition.

Further, the inlet end of the overflow pipe 50c is arranged with an inlet grill defining an insertion hole, and the water replenishment outlet of the water replenishment pipe 35c is inserted with the insertion hole.

In the embodiments, by fixing the water replenishment outlet of the water replenishment pipe 35c, the bidet 300 with an integrated built-in water tank can be prevented from loosening from the inlet end of the overflow pipe 50c in a shaking environment. In addition, the grill hole on the inlet grill does not obstruct the water intake of the overflow pipe 50c.

Further, the shell 14c further includes a front sidewall 19c disposed on the front side of the partition 20c; a first opening 27c is defined between the front sidewall 19c and the partition 20c and disposed at the bottom and corresponding to the front portion of the bedpan 12c; a second opening 28c is defined between the front sidewall 19c and the first rear sidewall 21c and disposed at the bottom; the partition 20c, the first rear sidewall 21c, the shell 14c, and the bedpan 12c are of an integrated ceramic structure.

In the embodiments, since the first opening 27c and the second opening 28c are reserved and the water tank 25c has an opening facing upward, it is easy to reach the outer surface of the bidet main body 11c from the outside through the first opening 27c, and to reach sides of the first rear sidewall 21c and the second rear sidewall 18c facing each other through the second opening 28c, such that the setting of the water tank 25c does not affect the profile of the bidet main body 11c and the shaping of additional structures on the first rear sidewall 21c, such as the connector 26c.

In a fourth embodiment, referring to FIGS. 26 to 30, a bidet 400 with an integrated built-in water tank proposed in the present disclosure includes a seat 10d, a water inlet assembly 30d, a jetting assembly 40d, and an overflow pipe 50d.

The seat 10d includes a bidet main body 11d, a shell 12d, and a water tank 19d; the bidet main body 11d includes a bedpan 111d and a drain pipe 112d connected to the bedpan 111d; the shell 12d is disposed at a periphery of the bidet main body 11d.

The water inlet assembly 30d and the jetting assembly 40d are both disposed in the water tank 19d; the water inlet assembly 30d includes a water inlet pipe 31d, a water valve assembly 32d connected in series with the water inlet pipe 31d, and the jetting assembly 40d includes a jetting pipe 41d and a water pump 42d connected in series with the jetting pipe 41d; the jetting pipe 41d is in communication with the bedpan 111d.

An inlet end of the overflow pipe 50d extends into the water tank 19d.

In the embodiments, the seat 10d is a main structure; the water inlet assembly 30d and the jetting assembly 40d are disposed on the seat 10d; the bidet main body 11d and the shell 12d of the seat 10d may be adopted from the related art; the bedpan 111d is configured to receive excrement, and the jetting assembly 40d is configured to jet water into an inner cavity of the bidet main body 11d, so as to discharge the excrement into a pipe connected to a septic tank through the drain pipe 112d. The drain pipe 112d is usually arranged with a water reservoir for odor prevention, and the drain pipe 112d may be further arranged with an upwardly-arched curved portion to prevent backflow. The shell 12d is not only a cosmetic part, but also provides support for the bidet main body 11d. The seat 10d may be installed either on a bottom surface or on a vertical surface, such as on a wall or on a stand having a vertical installation surface. Both the water inlet assembly 30d and the jet assembly 40d may be adopted from the related art; the water valve assembly 32d may be either a manual valve or an electromechanical automatic valve, such as a solenoid valve, or a purely mechanical automatic valve. The overflow pipe 50d may extend into the water tank 19d at the inlet end only, or the overflow pipe 50d may be located entirely within the water tank 19d.

As proposed by the present disclosure, for the bidet 400 with an integrated built-in water tank, the inlet end of the overflow pipe 50d extends into the water tank 19d arranged with the water inlet assembly 30d and the jetting assembly 40d, such that even if the water inlet assembly 30d malfunctions and results in an overfilling of the water, the excess water can be discharged out of the inlet end of the overflow pipe 50d, which thereby reduces the risk of a leakage of the water from the bidet. Furthermore, due to the structure of the overflow pipe 50d within the water tank 19d, the bidet 400 with an integrated built-in water tank is provided with a water level line defined by a mandatory standard.

Further, the outlet end of the overflow pipe 50d is in communication with the drain pipe 112d. In this way, the overflow pipe 50d and the drain pipe 112d can share a common connection to an external pipe.

Further, referring to FIGS. 31 and 32 together, in some embodiments, the shell 12d includes a bottom wall 13d, and a lower portion of the drain pipe 112d is integrally connected to the bottom wall 13d; a position, of an upper surface of the bottom wall 13d, adjacent to the drain pipe 112d is arranged with an installation tab 20d being hollow; an inner cavity of the installation tab 20d is in communication with the drain pipe 112d, a top of the installation tab 20d defines an

overflow installation hole **201d** in communication with the inner cavity of the installation tab **20d**, and a lower end of the overflow pipe **50d** is sealingly fixed to the overflow installation hole **201d**.

In the embodiments, the installation tab **20d** is set such that the overflow pipe **50d** can be arranged off-set from the drain pipe **112d**, thereby enabling the realization of easier installation and a relatively compact installation structure.

Further, the shell **12d** includes a front sidewall **14d**, a bottom wall **13d**, a left sidewall **15d**, a right sidewall **16d**, and a rear sidewall **17d**, and a bottom opening **18d** is defined between the front sidewall **14d** and the bottom wall **13d** facing a front portion of the bedpan **111d**.

The seat **10d** further includes a partition **21d** extending upwardly from the bottom wall **13d**, and the partition **21d**, the bottom wall **13d**, the left sidewall **15d**, the right sidewall **16d**, and the rear sidewall **17d** enclose to form the water tank **19d**; the water tank **19d** is opened upwardly; the installation tab **20d**, the partition **21d**, the shell **12d**, and the bedpan **111d** are of an integrated ceramic structure.

In the embodiments, the overflow pipe **50d** is integrally disposed within the water tank **19d**. By providing the partition **21d**, the shell **12d**, and the bedpan **111d** of an integrated ceramic structure, while retaining the bottom opening **18d**, the upwardly-opened water tank is formed by enclosing the partition **21d**, the bottom wall **13d**, the left sidewall **15d**, the right sidewall **16d**, and the rear sidewall **17d**, such that the space in a rear portion of the seat **10d** is fully utilized, and the formed water tank has a large capacity and can cooperate with the water pump **42d** for a long and stable flushing operation. Moreover, since the bottom opening **18d** is retained and the water tank has an opening facing upward, an outer surface of the bidet main body **11d** can be easily accessed from the outside, such that the setting of the water tank does not affect the shaping of the bidet main body **11d**. The opening on an upper portion of the water tank also facilitates the installation of a smart toilet cover, whereby a lower raised portion at a rear end of the smart toilet cover can be embedded in the water tank, thereby making the overall height of the product lower, which in turn enhances the installation adaptability or reduces the space occupation. Since the water tank is constructed of ceramic material and is integrally structured with the bidet main body **11d** and the rest of the shell **12d**, it is less likely to resonate with vibration of the water pump **42d**, which can provide the user with a better silent experience.

Further, referring to FIGS. 32 and 33, in some embodiments, in order to ensure that the overflow pipe **50d** is quickly installed and the lower end of the overflow pipe **50d** is sealed, an outer peripheral surface of the outlet end of the overflow pipe **50d** is arranged with a limiting flange **511d** and an elastic snap **512d**; the limiting flange **511d** and the elastic snap **512d** are spaced apart in a drainage direction of the overflow pipe **50d**, and the elastic snap **512d** is positioned lower than the position of the limiting flange **511d**; the bidet **400** with an integrated built-in cistern further includes a sealing ring **60d** sleeved on the outer peripheral surface of the outlet end of the overflow pipe **50d**, and the elastic snap **512d** abuts against an inner surface of the installation tab **20d**; the sealing ring **60d** is pressed between the limiting flange **511d** and the installation tab **20d** and is sealingly mated with an upper surface of the limiting flange **511d** and an upper surface of the installation tab **512d**, respectively.

Further, referring to FIG. 26, FIG. 18, FIG. 30, FIG. 31, and FIG. 33, in some embodiments, the overflow pipe includes an odor barrier structure so as to prevent odorous

gases within the drain pipe **112d** from spilling out into the indoor environment through the overflow pipe **50d**.

Further, the overflow pipe **50d** includes an inline section **51d** and a reservoir section **52d** connected to an upper end of the inline section **51d**, the inlet end of the overflow pipe **50d** being formed in the reservoir section **52d**, and the outlet end of the overflow pipe **50d** being formed at a lower end of the inline section **51d**.

In the embodiments, the reservoir section **52d** is provided such that when water is stored in the reservoir section **52d**, the odor in the drain pipe **112d** can be prevented from overflowing into the indoor environment through the overflow pipe **50d**. The specific shape of the reservoir section **52d** may not be particularly limited in the embodiments, as long as the water can be smoothly drained and the air communication between the inlet end and the outlet end of the overflow pipe **50d** can be blocked when the water level of the water tank **19d** exceeds the inlet end of the overflow pipe **50d**.

Further, the inline section **51d** extends in a vertical direction, a main portion of the reservoir section **52d** is in the shape of an arch with a concave side facing upward, and the reservoir section **52d** has a connection port arranged downwardly and connected to the upper end of the inline section **51d**.

In the embodiments, the arched reservoir section **52d** has less internal resistance such that the overflow pipe **50d** can drain faster; the reservoir section **52d** can be more easily connected to the inline section **51d** by providing the downward-facing connection port.

Further, the inline section **51d** is disposed adjacent to the drain pipe **112d** so as to better concentrate the drainage. In order to fully utilize the space of the water tank **19d** and to avoid interference between the reservoir section **52d** and the drain pipe **112d** during installation, the reservoir section **52d** is arranged on a side of the inline section **51d** away from the drain pipe **112d**.

Further, the rear sidewall **17d** of the shell **12d** defines a water inlet installation hole **171d**, and the water inlet assembly **30d** further includes a water inlet fitting **34d**; an outlet of the water inlet fitting **34d** is in communication with an inlet of the water inlet pipe **31d**; the water inlet fitting **34d** is removably connected to the water inlet installation hole **171d**.

The water inlet assembly **30d** further includes a water replenishment assembly **33d**; the water replenishment assembly **33d** includes a water replenishment valve **332d**, a water replenishment pipe **333d**, and a water replenishment outlet **331d**, the water replenishment valve **332d** being disposed adjacent to the water inlet fitting **34d**; a water replenishment inlet of the water replenishment pipe **333d** is connected to the water replenishment valve **332d**, and a water replenishment outlet **331d** of the water replenishment pipe **333d** is connected to the inlet end of the overflow pipe **50d**.

In the embodiments, the water inlet fitting **34d** can facilitate the connection of the water inlet pipe **31d** to the municipal water pipe and support the water inlet pipe **31d**. In some embodiments, an outlet of the water inlet pipe **31d** is disposed close to the bottom wall **13d**, such that less noise is generated during water replenishment. Since the water level of the water tank **19d** is too high and a scenario where overflow drainage is required through the overflow pipe **50d** is in a low frequency, if the reservoir section **52d** of the overflow pipe **50d** is left standing for a long period of time after water is first added, an odor is generated from the water stored in the reservoir section **52d**. When the reservoir

section 52d is replenished by the water replenishment assembly 33d in a timely manner, the water stored in the reservoir section 52d can be replaced before the odor is generated.

In a fifth embodiment, referring to FIGS. 34 to 37, a bidet 500 with an integrated built-in water tank proposed in the present disclosure includes a seat 10e, a water inlet assembly 30e, and a jetting assembly 40e; the seat 10e includes a bidet main body 11e, a shell 14e, and a partition 23e.

The bidet main body 11e includes a bedpan 12e and a drain pipe 13e connected to the bedpan 12e.

The shell 14e is disposed at a periphery of the bidet main body 11e; the shell 14e includes a front sidewall 15e, a bottom wall 16e, a left sidewall 17e, a right sidewall 18e, and a rear sidewall 19e; a bottom opening 24e is defined between the front sidewall 15e and the bottom wall 16e facing a front portion of the bedpan 12e.

The partition 23e extends upwardly from the bottom wall 16e, and the partition 23e, the bottom wall 16e, the left sidewall 17e, the right sidewall 18e, and the rear sidewall 19e enclose to form the upwardly-opened water tank 25e; the partition 23e, the shell 14e, and the bedpan 12e are of an integrated ceramic structure.

The water inlet assembly 30e and the jetting assembly 40e are both disposed in the water tank 25e; the water inlet assembly 30e includes a water inlet pipe 31e, a water valve assembly 32e connected in series to the water inlet pipe 31e, and the jetting assembly 40e includes a jetting pipe 41e and a water pump 42e connected in series to the jetting pipe 41e; the jetting pipe 41e is in communication with the bedpan 12e.

The rear sidewall 19e includes a first rear sidewall 20e and a second rear sidewall 21e disposed facing each other in a front-rear direction, and the second rear sidewall 21e defines a hanging hole 211e and a drain through hole 212e; the first rear sidewall 20e defines a water inlet installation hole 201e.

The partition 23e and the first rear sidewall 20e are disposed opposite to each other in the front-rear direction and both extend upwardly from the bottom wall 16e, and a front portion of the bedpan 12e protrudes from a front surface of the partition 23e; the partition 23e and the first rear sidewall 20e are disposed on a front side of the second rear sidewall 21e; an installation cavity 22e is defined between the first rear sidewall 20e and the second rear sidewall 21e, and the drain pipe 13e passes through the first rear sidewall 20e and has an external connection end 131e extending into the installation cavity 22e, the external connection end 131e being disposed at a position corresponding to the drain through hole 212e; the partition 23e, the first rear wall 20e, the bottom wall 16e, the left sidewall 17e, and the right sidewall 18e enclose to form the water tank 25e that is opened upwardly.

The bidet 500 with an integrated built-in water tank further includes an overflow pipe 50e passing through the first rear sidewall 20e; an inlet end of the overflow pipe 50e is disposed in the water tank 25e, and an outlet end of the overflow pipe 50e extends into the installation cavity 22e; the outlet end of the overflow pipe 50e is in communication with the external connection end 131e.

The bidet 500 with an integrated built-in tank further includes a side branch pipe 60e; an end of the side branch pipe 60e is in communication with an upper portion of the bedpan 12e and the other end of the side branch pipe 60e is in communication with the inlet end of the overflow pipe 50e.

The upper portion of the bedpan 12e defines a diversion groove 121e arranged horizontally, and the jetting pipe 41e

as well as the side branch pipe 60e are in communication with the diversion groove 121e. The diversion groove 121e has two rearwardly disposed corner portions, and the jetting pipe 41e and the side branch pipe 60e are connected to the two corner portions, respectively.

The overflow pipe 50e includes an odor barrier structure; the overflow pipe 50e includes an inline section and a reservoir section connected to an upper end of the inline section; the inlet end of the overflow pipe 50e is formed in the reservoir section; the odor barrier structure is formed in the reservoir section, the inline section extends along the front-rear direction, and the outlet end of the overflow pipe 50e is formed at a rear end of the inline section; a main portion of the reservoir section is in the form of an arch with a concave side facing upward.

The bidet 500 with an integrated built-in water tank further includes an extraction assembly (not shown), the extraction assembly including an extraction pipe and an extraction fan connected in series with the extraction pipe; an end of the extraction pipe is in communication with an upper portion of the bedpan 12e and the other end of the extraction pipe is in communication with a downstream portion of a reservoir area of the reservoir section.

In a sixth embodiment, referring to FIGS. 38 to 41, a bidet 600 with an integrated built-in water tank proposed in the present disclosure includes a seat 10f, a water inlet assembly, and a jetting assembly 40f; the seat 10f includes a bidet main body 11f, a shell 14f, and a partition 20f.

The bidet main body 14f includes a bedpan 12f and a drain pipe 13f connected to the bedpan 12f.

The shell 14f is disposed at a periphery of the bidet main body 11f; the shell 14f includes a front sidewall 15f, a bottom wall 16f, a left sidewall 17f, a right sidewall 18f, and a rear sidewall 19f; a bottom opening 21f is defined between the front sidewall 15f and the bottom wall 16f facing a front portion of the bedpan 12f.

The partition 20f extends upwardly from the bottom wall 16f, and the partition 20f, the bottom wall 16f, the left sidewall 17f, the right sidewall 18f, and the rear sidewall 19f enclose to form an upwardly-opened water tank 22f; the partition 20f, the shell 14f, and the bedpan 12f are of an integrated ceramic structure.

The water inlet assembly and the jetting assembly 40f are both disposed in the water tank 22f; the water inlet assembly includes a water inlet pipe 31f, a water valve assembly connected in series with the water inlet pipe 31f, and the jetting assembly 40f includes a jetting pipe 41f and a water pump 42f connected in series with the jetting pipe 41f; the jetting pipe 41f is in communication with the bedpan 12f.

The bidet 600 with an integrated built-in water tank further includes an overflow pipe 50f and a side branch pipe 60f; an inlet end of the overflow pipe 50f extends into the water tank 22f, and an outlet end of the overflow pipe 50f is in communication with the drain pipe 13f; an end of the side branch pipe 60f is in communication with an upper portion of the bedpan 12f, and the other end is in communication with the inlet end of the overflow pipe 50f; the upper portion of the bedpan 12f defines a diversion groove 121f arranged horizontally; both the jetting pipe 41f and the side branch pipe 60f are in communication with the diversion groove 121f.

The bidet 600 with an integrated built-in water tank further includes an overflow pipe 50f and an extraction assembly; an inlet end of the overflow pipe 50f extends into the water tank 22f, and an outlet end of the overflow pipe 50f is in communication with the drain pipe 13f; the overflow pipe 50f includes an odor barrier structure, and the overflow

21

pipe 50/f includes an inline section 51/f and a reservoir section 52/f connected to an upper end of the inline section 51/f; the inlet end of the overflow pipe 50/f is formed in the reservoir section 52/f, the odor barrier structure is formed in the reservoir section 52/f, and the outlet end of the overflow pipe 50/f is formed in a lower end of the inline section 51/f; the inline section 51/f extends in a vertical direction, and a main portion of the reservoir section 52/f is in the form of an arch with a concave side facing upward; the reservoir section 52/f has a connection port arranged downwardly to be connected to the upper end of the inline section 51/f; the extraction assembly includes an extraction pipe 51/f and an extraction fan connected in series to the extraction pipe 51/f; an end of the extraction pipe 51/f is in communication with an upper portion of the bedpan 12/f, and the other end is in communication with the inline section 51/f.

The fifth and sixth embodiments have the same technical effect as one or more of the first to fourth embodiments, respectively, and will not be repeated herein. In the fifth and sixth embodiments, in an event that the drain pipe 13e, 13/f becomes clogged and the user presses the flush button, the water within the bedpan 12e, 12/f can be introduced into the overflow pipe 50e, 50/f from the side branch pipe 60e, 60/f, so as to avoid sewage leakage. In addition, the odor generated in the bedpan 12e, 12/f can be discharged into the overflow pipes 50e, 50/f through the extraction pipe (not shown in the fifth embodiment, labeled as 51/f in the sixth embodiment), and the water accumulated in the overflow pipe 50e, 50/f can act as a one-way valve for the gas discharged from the extraction pipe, so as to force the odor-bearing gas to be discharged into the downstream of the overflow pipe 50e, 50/f, and thus be discharged to a public sewer or to the outdoor environment.

Finally, it should be noted that the above embodiments are only intended to illustrate the technical solutions of the present disclosure, not to limit them; although the present disclosure has been described in detail referring to the foregoing embodiments, those skilled in the art should understand that it is still possible to modify the technical solutions recorded in the foregoing embodiments or replace some of the technical features therein; and such modifications or replacements do not drive the essence of the corresponding technical solutions out of the spirit and scope of the technical solutions of the various embodiments of the present disclosure.

What is claimed is:

1. A bidet with an integrated built-in water tank, comprising
a seat,
a water inlet assembly, and
a jetting assembly; wherein the seat comprises a bidet main body, a shell, and a partition; the bidet main body comprises a bedpan and a drain pipe in communication with the bedpan; the shell is arranged at a periphery of the bidet main body; the shell comprises a front sidewall, a bottom wall, a left sidewall, a right sidewall, and a rear sidewall; a bottom opening is defined between the front sidewall and the bottom wall facing a front portion of the bedpan;
the partition extends upwardly from the bottom wall; the partition, the bottom wall, the left sidewall, the right sidewall, and the rear sidewall enclose to form a water tank that is opened upwardly; the partition, the shell, and the bedpan are of an integrated ceramic structure; the water inlet assembly and the jetting assembly are disposed in the water tank; the water inlet assembly comprises a water inlet pipe and a water valve assem-

22

bly connected in series to the water inlet pipe; the jetting assembly comprises a jetting pipe and a water pump connected in series to the jetting pipe, and the jetting pipe is in communication with the bedpan; wherein the rear sidewall defines a water inlet installation hole, and the water inlet assembly further comprises a water inlet fitting; an outlet of the water inlet fitting is connected to an inlet of the water inlet pipe; the water inlet fitting is removably connected to the water inlet installation hole.

5 2. The bidet according to claim 1, wherein the rear sidewall comprises a base and a bulge that bulges inwardly from the base; the bulge defines a cavity that is opened toward an outside; the water inlet installation hole is defined on the bulge and is in communication with the cavity; an outer end of the water inlet fitting is disposed in the cavity.

10 3. The bidet according to claim 1, wherein the water inlet fitting comprises a fitting body, a sealing ring, and a fastener; the fitting body comprises a tube portion and a limiting flange disposed on an outer peripheral surface of an inner end of the tube portion, and the outer peripheral surface of the tube portion defines an outer thread; the tube portion passes through the water inlet installation hole; the limiting flange is disposed on an inner side of the rear sidewall, the sealing ring is disposed between the limiting flange and the rear sidewall, and the fastener is threadedly mated with the tube portion and disposed on an outer side of the rear sidewall.

15 4. A bidet with an integrated built-in water tank, comprising

20 a seat,
a water inlet assembly, and
a jetting assembly; wherein the seat comprises a bidet main body, a shell, and a partition; the bidet main body comprises a bedpan and a drain pipe in communication with the bedpan; the shell is arranged at a periphery of the bidet main body; the shell comprises a front sidewall, a bottom wall, a left sidewall, a right sidewall, and a rear sidewall; a bottom opening is defined between the front sidewall and the bottom wall facing a front portion of the bedpan;

25 the partition extends upwardly from the bottom wall; the partition, the bottom wall, the left sidewall, the right sidewall, and the rear sidewall enclose to form a water tank that is opened upwardly; the partition, the shell, and the bedpan are of an integrated ceramic structure; the water inlet assembly and the jetting assembly are disposed in the water tank; the water inlet assembly comprises a water inlet pipe and a water valve assembly connected in series to the water inlet pipe; the jetting assembly comprises a jetting pipe and a water pump connected in series to the jetting pipe, and the jetting pipe is in communication with the bedpan; wherein the partition extends upwardly to be connected to the bedpan, and an upper portion of the rear sidewall defines a window connected to an outside.

30 5. The bidet according to claim 4, wherein the drain pipe has a curved portion extending into the water tank; the drain pipe is arranged in the middle in a left-right direction; the water inlet assembly is disposed on a first side of the drain pipe, and the water pump is disposed on a second side of the drain pipe, the first side and the second side being opposite to each other in the left-right direction.

35 6. A bidet with an integrated built-in water tank, comprising
a seat,
a water inlet assembly, and

a jetting assembly; wherein the seat comprises a bidet main body, a shell, and a partition; the bidet main body comprises a bedpan and a drain pipe in communication with the bedpan; the shell is arranged at a periphery of the bidet main body; the shell comprises a front sidewall, a bottom wall, a left sidewall, a right sidewall, and a rear sidewall; a bottom opening is defined between the front sidewall and the bottom wall facing a front portion of the bedpan;

the partition extends upwardly from the bottom wall; the partition, the bottom wall, the left sidewall, the right sidewall, and the rear sidewall enclose to form a water tank that is opened upwardly; the partition, the shell, and the bedpan are of an integrated ceramic structure; the water inlet assembly and the jetting assembly are disposed in the water tank; the water inlet assembly comprises a water inlet pipe and a water valve assembly connected in series to the water inlet pipe; the jetting assembly comprises a jetting pipe and a water pump connected in series to the jetting pipe, and the jetting pipe is in communication with the bedpan; wherein an inner wall surface of an upper portion of the bedpan defines an annular flushing groove; the jetting assembly further comprises a three-way valve; the jetting pipe comprises a main path, a first branch path connected to an outlet of the three-way valve, and a second branch path connected to another outlet of the three-way valve; the main path is connected to an outlet of the water pump and an inlet of the three-way valve; an outlet of the first branch path is in communication with a bottom of the bedpan, and an outlet of the second branch path is in communication with the annular flushing groove on the upper portion of the bedpan.

7. The bidet according to claim 6, wherein the partition extends upwardly to be connected to the bedpan, and the partition defines a through hole for the second branch path to pass through.

8. The bidet according to claim 1, wherein, the rear sidewall comprises a first rear sidewall and a second rear sidewall disposed facing each other in a front-rear direction, the second rear sidewall defines a hanging hole and a drain through hole, and the first rear sidewall defines the water inlet installation hole; the partition and the first rear sidewall are disposed opposite to each other in the front-rear direction and both extend upwardly from the bottom wall, and a front portion of the bedpan protrudes from a front surface of the partition; the partition and the first rear sidewall are disposed on a front side of the second rear sidewall; an installation cavity is defined between the first rear sidewall and the second rear sidewall, and the drain pipe passes through the first rear sidewall and has an external connection end extending into the installation cavity, the external connection end being disposed at a position corresponding to the drain through hole; the partition, the first rear sidewall, the bottom wall, the left sidewall, and the right sidewall enclose to form a water tank that is opened upwardly.

9. The bidet according to claim 8, further comprising an overflow pipe passing through the first rear sidewall; wherein an inlet end of the overflow pipe is disposed in the water tank, and an outlet end of the overflow pipe extends into the installation cavity and is in communication with the external connection end.

10. The bidet according to claim 9, wherein the seat further comprises a connector protruding on a rear surface of the first rear sidewall and connected to an outer peripheral

surface of the external connection end; an inner cavity of the connector is in communication with an inner cavity of the external connection end; an overflow installation hole is defined on the first rear sidewall corresponding to the connector and in communication with the inner cavity of the connector, and the outlet end of the overflow pipe is sealingly fixed to the overflow installation hole; the partition, the first rear sidewall, the shell, the bedpan, and the connector are of an integrated ceramic structure.

11. The bidet according to claim 9, wherein the overflow pipe comprises an odor barrier structure; the overflow pipe further comprises an inline section and a reservoir section connected to an upper end of the inline section; the inlet end of the overflow pipe is formed at the reservoir section; the odor barrier structure is formed at the reservoir section, and the outlet end of the overflow pipe is formed at a lower end of the inline section; the inline section extends in a vertical direction, and a main portion of the reservoir section is in a form of an arch with a concave side facing upward; the reservoir section has a connection port arranged downwardly to be connected to the upper end of the inline section; the water inlet assembly further comprises a water replenishment assembly; the water replenishment assembly comprises a water replenishment valve, and a water replenishment pipe; a water replenishment inlet of the water replenishment pipe is connected to the water replenishment valve, and a water replenishment outlet of the water replenishment pipe is connected to the inlet end of the overflow pipe.

12. The bidet according to claim 9, further comprising a side branch pipe; wherein an end of the side branch pipe is in communication with an upper portion of the bedpan, and the other end of the side branch pipe is in communication with the inlet end of the overflow pipe.

13. The bidet according to claim 12, wherein, the overflow pipe comprises an odor barrier structure; the overflow pipe further comprises an inline section and a reservoir section connected to an upper end of the inline section; the inlet end of the overflow pipe is formed at the reservoir section; the odor barrier structure is formed at the reservoir section, the inline section extends along a front-rear direction, and the outlet end of the overflow pipe is formed at a rear end of the inline section; a main portion of the reservoir section is in a form of an arch with a concave side facing upward; the bidet further comprises an extraction assembly, the extraction assembly comprising an extraction pipe and an extraction fan connected in series with the extraction pipe; an end of the extraction pipe is in communication with the upper portion of the bedpan, and the other end of the extraction pipe is in communication with a downstream portion of a reservoir area of the reservoir section.

14. The bidet according to claim 8, wherein the shell further comprises the front sidewall disposed on the front side of the partition; a first opening is defined between the front sidewall and the partition and disposed at a bottom and corresponding to the front portion of the bedpan; a second opening is defined between the front sidewall and the first rear sidewall and disposed at the bottom; the partition, the first rear sidewall, the shell, and the bedpan are of an integrated ceramic structure.

15. The bidet according to claim 1, further comprising an overflow pipe; wherein an inlet end of the overflow pipe extends into the water tank, and an outlet end of the overflow pipe is in communication with the drain pipe;

25

the shell comprises the bottom wall, and a lower portion of the drain pipe is integrally connected to the bottom wall; a position, of an upper surface of the bottom wall, adjacent to the drain pipe is arranged with an installation tab being hollow; an inner cavity of the installation tab is in communication with the drain pipe, a top of the installation tab defines an overflow installation hole in communication with the inner cavity of the installation tab, and a lower end of the overflow pipe is sealingly fixed to the overflow installation hole; the installation tab, the partition, the shell, and the bedpan are of an integrated ceramic structure.

16. The bidet according to claim 15, wherein, an outer peripheral surface of the outlet end of the 15 overflow pipe is arranged with a limiting flange and an elastic snap; the limiting flange and the elastic snap are spaced apart in a drainage direction of the overflow pipe, and the elastic snap is positioned lower than a position of the limiting flange;

the bidet further comprises a sealing ring sleeved on the outer peripheral surface of the outlet end of the overflow pipe, and the elastic snap abuts against an inner surface of the installation tab; the sealing ring is 20 pressed between the limiting flange and the installation tab and is sealingly mated with an upper surface of the limiting flange and an upper surface of the installation tab, respectively.

17. The bidet according to claim 15, wherein, the overflow pipe comprises an odor barrier structure; the 30 overflow pipe further comprises an inline section and a reservoir section connected to an upper end of the inline section; the inlet end of the overflow pipe is formed at the reservoir section; the odor barrier structure is formed at the reservoir section, and the outlet 35 end of the overflow pipe is formed at a lower end of the inline section; the inline section extends in a vertical direction, and a main portion of the reservoir section is in a form of an arch with a concave side facing upward;

26

the reservoir section has a connection port arranged downwardly to be connected to the upper end of the inline section.

18. The bidet according to claim 1, further comprising an 5 overflow pipe and a side branch pipe; wherein an inlet end of the overflow pipe extends into the water tank, and an outlet end of the overflow pipe is in communication with the drain pipe; an end of the side branch pipe is in communication with an upper portion of the bedpan, and the other end of the side branch pipe is in communication with the inlet 10 end of the overflow pipe; the upper portion of the bedpan defines a diversion groove arranged horizontally; both the jetting pipe and the side branch pipe are in communication with the diversion groove.

19. The bidet according to claim 1, wherein, the bidet further comprises an overflow pipe and an 15 extraction assembly; an inlet end of the overflow pipe extends into the water tank, and an outlet end of the overflow pipe is in communication with the drain pipe; the overflow pipe comprises an odor barrier structure, and the overflow pipe comprises an inline section and a reservoir section connected to an upper end of the inline section; the inlet end of the overflow pipe is formed at the reservoir section, the odor barrier structure is formed at the reservoir section, and the outlet 20 end of the overflow pipe is formed at a lower end of the inline section; the inline section extends in a vertical direction, and a main portion of the reservoir section is in a form of an arch with a concave side facing upward; the reservoir section has a connection port arranged downwardly to be connected to the upper end of the inline section;

the extraction assembly comprises an extraction pipe and an extraction fan connected in series to the extraction pipe; an end of the extraction pipe is in communication with an upper portion of the bedpan, and the other end of the extraction pipe is in communication with the inline section.
